UNITED STATES PATENT OFFICE.

HARRY W. HOLMES, OF RAHWAY, NEW JERSEY, ASSIGNOR TO THE REGINA CORPORATION, OF RAHWAY, NEW JERSEY, A CORPORATION OF NEW JERSEY.

ATTACHMENT FOR BAGS.

Application filed May 16, 1923. Serial No. 639,268.

To all whom it may concern:

Be it known that I, HARRY W. HOLMES, a citizen of the United States, and resident of Rahway, county of Union, State of New Jersey, have invented certain new and useful Improvements in Attachments for Bags, of which the following is a specification.

My invention relates to attachments for bags and has for its object to provide a device of simple and novel construction intended for combination primarily with the dust bags of suction cleaners and arranged in a manner to automatically open or spread the one end of the bag when desired, to permit the contents thereof to be readily removed therefrom. The invention will be fully described hereinafter.

In the accompanying drawings which show an example of the invention without defining its limits, Fig. 1 is an elevation of the bag with the invention applied thereto; Fig. 2 is a perspective view thereof showing said bag with its one end automatically open or spread; Fig. 3 is a cross section on an enlarged scale on the line 3—3 of Fig. 1; Fig. 4 is a side view of the attachment; Fig. 5 is a plan view thereof and Fig. 6 is an elevation of one form of bag embodying the invention.

As shown in the drawings the attachment comprises an expandible member consisting of two flat springs 10 pivotally connected together at their opposite ends preferably by means of hinges 11 as shown in Fig. 4; the tension of the springs 10 is such that the expandible member normally tends to assume the position shown in Fig. 5 in which the springs are spread apart. The expandible member is incorporated in the bag 12 which may be of any customary construction, for instance, by being enclosed in a hem 13 as shown in Figs. 1 and 3; an example of the bag 12 in the form of a dust collector for attachment to a suction cleaner, is shown in Fig. 6. The end of the bag on which the expandible member is located is maintained in its normal closed position by means of the customary clamp 14 which is slidably spaced over the end of the bag as indicated in Figs. 1 and 3 and serves to clamp the springs 10 together in the position shown best in Fig. 3 in which the hemmed end of the bag is efficiently and completely closed. The clamp 14 may be provided with the customary spring 15 whereby the bag is maintained in

place upon the suction cleaner. When it is desired to empty the bag it is disconnected from the suction cleaner in the well known way after which the clamp 14 is slidably withdrawn as indicated in Fig. 1 whereby 60 its restraining effect is removed. As soon as said clamp has been fully withdrawn from the bag, that end thereof, because of the inherent expansibility of the springs 10, will be automatically opened or spread to the 65 position shown in Fig. 2. The action of the springs 10 will maintain this end of the bag in this open condition and thereby permit the contents thereof to be readily emptied and completely removed from the 70 bag. To again close the bag the springs 10 are simply compressed toward each other to permit the clamp 14 to be again slidably placed over the hem 13 to maintain said springs in the condition shown in Fig. 3. 75

While the invention is primarily intended for use in bags comprising a part of the well known suction cleaners, it obviously will be useful in connection with bags of other types in which it is desired, at periodic times, to 80 maintain an end thereof in an open spread condition. The attachment is of particular usefulness in connection with suction cleaner bags which have always been difficult to empty and in which the removal of the dirt 85 and other contents of the bag is always a messy and dirty operation. With the present attachment the emptying of the bag becomes the simplest kind of an operation, easily accomplished, without any soiling of the person emptying the bag. 90

Various changes in the specific form shown and described may be made within the scope of the claims without departing from the spirit of my invention. 95

I claim:

1. The combination of a bag, a resilient device comprising complemental members each having an inherent resiliency in its entirety tending to spread said device into a symmetrical open position, said device being incorporated in said bag at the mouth thereof and means for clamping the complemental members of said resilient device in straight line surface engagement with each other whereby the mouth of said bag is closed against the inherent resiliency of said device. 100

2. The combination of a bag for suction cleaners having a hem at one end, a pair of flat springs hinged together at their oppo- 110

site ends and fixed in said hem, said springs having an inherent elasticity tending to spread symmetrically apart whereby said end of the bag is automatically spread to an 5 open position, and a clamp arranged to be slidably connected with said bag to maintain said springs in straight surface engagement with each other against spreading and thereby close said end of the bag.

10 3. An attachment for automatically spread-

ing the mouth of a bag, comprising a pair of complemental flat springs pivotally connected with each other at opposite ends and each having an inherent elasticity tending, at all times, to systematically bow each of 15 said springs outwardly in opposite directions away from each other on said pivots.

In testimony whereof I have hereunto set my hand.

HARRY W. HOLMES.
